(57) **CLAIM**

We claim the ornamental design for a mincer, as shown and described.

DESCRIPTION

FIG. 1 is a perspective view of a mincer according to the new design in closed position;

FIG. 2 is a left side view of a mincer according to the new design shown in FIG. 1;

FIG. 3 is a right side view of a mincer according to the new design shown in FIG. 1;

FIG. 4 is a front view of a mincer according to the new design shown in FIG. 1;

FIG. 5 is a rear view of the mincer shown in FIG. 1;

FIG. 6 is a bottom view of the mincer shown in FIG. 1;

FIG. 7 is a top view of the mincer shown in FIG. 1;

FIG. 8 is a perspective view of the mincer shown in FIG. 1 in open position;

FIG. 9 is a front view of the mincer according to the new design shown in FIG. 8; and,

FIG. 10 is a bottom view of the mincer according to the new design shown in FIG. 8.

Features shown in broken lines form no part of the claimed design.
